UNITED STATES PATENT OFFICE.

LESTER C. SMITH, OF ROME, NEW YORK, ASSIGNOR TO COE BRASS MANUFACTURING COMPANY, OF TORRINGTON, CONNECTICUT.

TUBE-FORMING MACHINE.

No. 922,536.

Specification of Letters Patent.

Patented May 25, 1909.

Application filed August 10, 1903. Serial No. 169,049.

To all whom it may concern:

Be it known that I, LESTER C. SMITH, of Rome, in the county of Oneida and State of New York, have invented certain new and useful Improvements in Tube-Forming Machines; and I do hereby declare that the following is a full, clear, and exact description thereof, which will enable others skilled in the art to which it appertains to make and 10 use the same, reference being had to the accompanying drawings, and to the characters of reference marked thereon, which form part of this specification.

The object of my invention is to provide a 15 tube forming machine, in which a completely closed tube is formed in four passes through rolls, and in which certain novel features of construction are embodied.

In the drawing, Figure 1 shows a side elevation of a machine embodying the features of my improvements, Fig. 2 shows an end view of the machine, showing the point at which the material enters, and the mechanism for lubricating one side of the strip and 25 placing tension thereon, as well as clipping the edges of the strip. Fig. 3 shows a side elevation of the part shown in Fig. 2. Fig. 4 shows a detail in sections of the mechanism for chamfering or cutting the edge of the 30 strip. Fig. 5 shows a cross section of the mechanism for holding and placing a tension on the strip. Figs. 6, 7, 8 and 9 show four sets of rolls for giving form to the strip. Figs. 10, 11, 12, 13, 14 and 15 show the successive 35 operations which the machine is intended to perform. Fig. 16 shows a plan view of the parts shown in Figs. 2 and 3.

Referring to the reference letters and figures in a more particular description, A indicates the first set of rolls; B the second set; C the third set and D the fourth or last set of rolls employed in forming the tube. In advance of the train of rolls mentioned is located the device E for lubricating the under 45 side of the strip, clipping the edges thereof, and putting tension on the strip. This device E consists of a body portion 2, having a platform or table 3 on which the strip of material to be operated is adapted to rest and slide. For pressing the strip on to the table, and thereby placing a tension thereon, there is provided a friction plate 4, the under side of which is plain or flat and substantially conforms to the surface of the table 3. At either 50 side the clamping plate 4 are provided verti-

cal walls 4^a, in which are provided inclined grooves. These inclined grooves are adapted to receive the inclined ribs 5 provided on the laterally slideable pieces 6. These side pieces 6 are adapted, also, to act as guides for the edge of the material. These sides 6 are mounted on slides in the body 2 to move transversely to the line of the strip, and are operated inwardly and outwardly from the central line by means of the right and left-hand screws 7 and 8 provided on the shaft 9, extending through or under the frame, and having its end extended to receive a wrench for manipulating the screws. The amount that the sides open and close is comparatively little and not sufficient to disengage the slide ribs 5 from the grooves in the clamping plate. 60

On the outer end of the shaft 9 there is secured an arm or crank 10, which has a pin 11 engaging between projections 12, 12 on one side of the clamping plate 4, and serving to move the clamping plate backward and forward to a limited extent, and, on account of it being mounted on the inclined ribs 5, causing it to move toward and from the surface of the table 3. 70

For limiting the movement of the clamping plate 4 in the direction toward the rollers, there is provided a set screw 13 adapted to engage with a cross bar 14 and stop the forward movement of the clamping plate 4. 75

For clipping the edges of the material, there is provided a rotatable cutter 20. This cutter is mounted on a shaft 21, supported in a movable bearing 22, which bearing is adjustable by a kind of ball and socket joint arrangement in the piece 23, constituting a portion of the side 6. The arrangement of these parts is such that the cutter 20 can be adjusted to any desired angle with reference to the plane of the material to be operated upon. 90

For lubricating the under side of the strip of the material to be operated upon, there is provided in advance of the receiving end of the device 3 a pad of felt, or other suitable material, 30. This pad projects from a holder 31, which holder is mounted on a swinging arm 32 operated by a toggle joint lever mechanism 33, by means of which it 100 may be lowered out of operative position. The whole device E is vertically adjustable to adapt to line with the rolls A by means of a vertical slide or guide 35 and an adjusting screw 36. 110

The first set of rolls A (see Fig. 6) consists of a grooved roll and a ribbed roll, the latter adapted to enter the groove of the former, and the forms of the rolls being such as to turn in the edges of the strip of material to a circle or curvature, substantially that of the completed tube (see Fig. 12). The second set of rolls, B, (see Fig. 7) also consists of a grooved roll and ribbed roll, and, as compared with the former set, the set B has a groove and rib for giving a comparatively sharp bend to the middle of the strip of material, and forming it to a portion of a circle of a less diameter than the circle of the finished tube (see Fig. 13). The set C of rolls (see Fig. 8) consists of two grooved rolls, and, in addition, the face of the lower roll is adapted to enter the groove of the upper roll to some extent. The groove in the lower roll is, as to its working face, curved or circular and formed on a circle of less diameter than the completed tube (see Fig. 14). The grooved or working face in the upper roll is formed on a circle of larger diameter than that of the lower roll. The set of rolls D (see Fig. 9) each have grooved faces, and the grooves are of semi-circular shape and the two together adapted to form a circle of substantially the same diameter as that of the completed tube.

The operation of the machine is as follows: In starting a strip, the operator, with a suitable wrench, turns the shaft 9 so as to spread or separate the sides 6, 6 and move back, and thereby elevate the clamping plate 4 away from the face of the table 3. The end of the strip can then be inserted and forced through the device 3 until it engages with the first set of rolls A. The device E is then operated to close onto the strip by turning the shaft 9 in the opposite direction from that described. This forces in the side walls 6 and forces down the clamping plate 4, thereby tightly gripping the strip and requiring a considerable tension or draw on the part of the rolls to move the strip through the device 3. At the time that the side pieces 6 are closed in, the edge trimmers or cutters 20 are moved up to the edges of the strip and as the strip starts to move forward, they will cut into the edge and begin to perform the office of trimming off the edge for which they are intended. The strip of material to be operated upon is roughly represented in Fig. 10 of the drawing, and indicated by X. After being operated on by the cutters 20, it is shown in Fig. 11 and indicated by X'. After passing through the first set of rolls A, the form of the strip is approximately shown in Fig. 12 and indicated by X''. In this form the edges a, a are turned inwardly to a segment of the circle, substantially that of the completed tube. In the pass through the rolls B, the strip is given a comparatively sharp bend in the middle. After the strip

has passed through the rolls B, it is of approximately the form shown in Fig. 13 and indicated by X'''. It has curvature at the middle, as indicated at b, of less diameter than the circle of the completed tube. In the pass through the rolls C, the tube is closed in to the oval form shown in Fig. 14, with the meeting edges in the large end of the oval. In the final pass through the rolls D, the tube is given a complete circular form and there is obtained a tube wherein there is a tension or spring pressing the meeting edges together, and the common tendency to spring apart at the edges is obviated. At the meeting edges, the tube will have a V shaped groove, which is adapted to be filled with suitable brazing mixture, and after being heated, the edges are thereby brazed together, forming a complete tube.

What I claim as new and desire to secure by Letters Patent is:

1. In a tube forming machine, the combination with the set of drawing and forming rolls of a tension and guiding device, consisting of a fixed table and a clamping plate and edge guides for the strip of material arranged in advance of the said rolls, substantially as set forth.

2. In a tube forming machine, the combination with the drawing and forming rolls of a guide and tensioned device, consisting of a fixed table, a clamping plate and adjustable slide plates operating in connection with the fixed table, and edged trimming-cutters provided at the delivery end of the fixed table, substantially as set forth.

3. In a tube forming machine, a set of rolls for forming tube in four passes, the first pair formed and adapted to operate to turn in the edges of the strip to substantially the curvature of the finished tube, the second pair formed and adapted to operate to give a relatively sharp transverse bend to the middle portion of the strip and bring it to a curvature less than that of the completed tube, the third pair formed and adapted to close the tube into an oval form with the meeting edges in the larger end of the oval, and the fourth pair formed and adapted to give a final circular form to the tube and expand or open the sharp bend formed by the second pair of rolls, substantially as set forth.

4. A tube forming machine comprising an adjustable guide, a pair of oppositely placed, angularly disposed rotary scarfing knives, a pair of rolls, one of which is vertically movable relative to the other, together with successive pairs of shaping rolls, the last pair of which have concavities on their surface and of such shape that pressure will be exerted upon the top and bottom of the shaped tube fed between them.

5. A tube forming machine comprising a guide, means for scarfing the sides of the strip fed through the guide, a series of pairs

of rolls, the first pair adapted to exert a preliminary pressure upon the material to be acted upon before rolling and the last pair of rolls adapted to exert pressure only upon the top and bottom of the tubular body fed between them.

6. A tube forming machine, comprising a series of adjustable rolls with one roll of the first pair adapted to be given a quick vertical movement relative to the opposite roll of the

pair, and a guiding and scarfing attachment vertically and laterally adjustable relative to the rolls.

In witness whereof, I have affixed my signature, in presence of two witnesses, this 15
3rd day of Aug. 1903.

LESTER C. SMITH.
